UNITED STATES PATENT OFFICE.

JESSE L. FAIRBANKS, OF MARION, OHIO.

EXCAVATOR.

1,078,842.

Specification of Letters Patent. Patented Nov. 18, 1913.

Application filed August 24, 1911. Serial No. 645,721.

To all whom it may concern:

Be it known that I, JESSE L. FAIRBANKS, a citizen of the United States, residing at Marion, in the county of Marion and State 5 of Ohio, have invented a new and useful Excavator, of which the following is a specification.

This invention relates to an improvement in excavators.

10 The primary object of this invention is to provide an excavator in which the dipper supporting arm travels in a fixed plane during its load-receiving movement.

15 A further object of the invention is to provide a simple and efficient driving mechanism which will participate in the longitudinal movement of the handle.

In the drawings;—Figure 1 is a side elevation of the complete apparatus. Fig. 2 20 is a detail view of the dipper arm driving mechanism. Fig. 3 is a detail view of the engine mounting. Fig. 4 is a side elevation showing a modified form of driving mechanism. Fig. 5 is a detail of the driving 25 mechanism.

In the drawings, 10 designates the car or support for the excavator which supports the boom 11 in the usual manner. This boom is supported by a beam 12, shroud 14 30 connecting said boom and beam. The boom 11 which supports the sheave 15 is of the usual construction, being formed of spaced parallel beams each of which is provided with a rack 17. The dipper arm 18 is sup-

35 ported between the parallel beams being also formed of spaced parallel beams which are provided with racks 19. The racks which are arranged on the parallel beams of the main boom are provided with portions 17'

40 which extend beyond the edges 17" of the beam. The bed plate 20 of the engine 21 is arranged to slide on the boom, said bed plate being formed with flanges 24 which extend beneath the portions 17" of the racks

45 17. The engine 21 is mounted on a carriage including a bed plate 20, the pitman 21' of said engine, driving the shaft 25 on the end portions of which the gears 26 are mounted.

The shaft 25 is supported by the side plates 50 27 which are secured to the engine bed and said gears mesh with the larger gears 28 arranged on a shaft 29 which is also supported by said plate. The shaft 29 is provided with gears 30, 31, 32 and 33, the gears 30 and 31 55 being arranged to engage the racks 17 and the gears 32 and 33 the racks 19 which are

arranged on the handle. The yoke 20' which is supported by the shaft 29 contacts with the edges of the beams which constitute the dipper arm thus holding the gears 32 and 33 in mesh with racks 19. It will thus be noted that as the engine drives the shaft 25 in one direction, shaft 29, will, through the gears 32 and 33, force the dipper arm downward and consonant with this 65 downward pressure the gears 30 and 31 will move the dipper arm longitudinally through their contact with the rack, the engine participating in the longitudinal movement of the dipper arm.

70 Steam is supplied to the reversing valve of the engine by pipes 34, 35, and 36, which are connected by universal joints 39 which allow the engine to participate in its longitudinal movement. The engine is controlled by a lever 40 mounted on the car, said lever causing the rotation of a shaft 41 which in turn drives the shaft 42, the shafts being connected by a universal coupling 43. A gear 44 is mounted on the 75 shaft 42 said shaft passing through said gear, said gear being adapted to mesh with a gear 45 which actuates the reversing valve of the engine, the engine in this manner being controlled regardless of its position on 80 the boom.

85 It will be noted from the foregoing that the arm which supports the dipper is maintained perpendicular to the ground in its load receiving movement, and although the 90 driving mechanism effectually imparts longitudinal and vertical movement to the arm, driving mechanism other than that shown might be substituted and the consonant vertical and longitudinal movement secured.

95 In the modified form of driving mechanism, the motor is mounted on the car, and the shaft 29 is rotated by means of a mechanism similar to the mechanism for operating the reversing valve of the engine shown in Fig. 1. This mechanism consists of the square shaft 34' which imparts movement to a pinion 35' supported by the bracket 36', said pinion 35' meshing with a pinion 37' arranged on the end portion of the shaft 25'. The shaft 34' is driven by means of a second shaft 38, the shaft being connected by a universal coupling 39', the shaft 38 being supported by a bracket 40'. Mounted on said shaft is a disk 41' which bears against the 105 friction gear 42' which is driven by the motor 43'. The disk 41' is moved across the 110

face of the friction gear 42' by means of the lever 43'', the movement of the shaft 34' in this manner being reversed. It will be noted by this construction that the same movement will be imparted to the dipper arm as in the construction shown in Fig. 1, the shaft 34' being allowed to participate in the movement of the boom by means of the universal coupling 39', said shaft sliding 10 freely through the pinion 36' as the dipper arm is advanced longitudinally.

15 The many advantages of an excavator of this construction will be clearly apparent as it will be noted that a straight line cut is secured, with the dipper arm at any angle, the same rotary movement which propels the arm in its load-receiving stroke, consonantly pressing said arm downwardly to prevent the same from traveling in an arc.

20 Particular attention is called to the fact that an excavator of this character may be easily and economically constructed, the various parts being such as may be readily assembled.

25 What is claimed is:—

1. An excavator including a boom, a rack thereon, a dipper arm, a rack upon the arm, a carriage slideable longitudinally along the boom, a gear supported on the carriage and 30 meshing with the boom rack, a gear on the carriage and meshing with the arm rack to support the arm, said gears being revoluble together about a common axis to simultaneously raise or lower the arm and actuate the carriage; and power driven means movable with the carriage for actuating the gears.

2. An excavator including a boom, a rack thereon, a dipper arm, a rack upon the arm, a carriage slideable longitudinally along the boom, a gear supported on the carriage and 40 meshing with the boom rack, a gear on the

carriage and meshing with the arm rack to support the arm, said gears being revoluble together about a common axis to simultaneously raise or lower the arm and actuate the carriage, means engaging the shaft and 45 slidably engaged by the arm for holding the arm rack in mesh with its gear, and power driven means movable with the carriage for 50 actuating the gears.

3. An excavator including a boom, racks thereon, a carriage slidably engaging the racks, a dipper arm, racks thereon, a shaft journaled on the carriage, gears upon the 55 shaft and meshing with and constituting pivots for the arm racks, means extending between the arm racks and their gears and engaging the shaft for holding the racks and 60 gears in mesh, gears upon the shaft and meshing with the boom racks, and power driven means upon the carriage for actuating all of the gears simultaneously.

4. An excavator including a boom, a rack 65 extending longitudinally of the boom, a dipper arm, a rack upon the dipper arm, a carriage slidably mounted on the boom, a shaft journaled on the carriage, means engaging the shaft and slidably engaged by the arm 70 for holding the arm against movement away from the shaft, a gear on the shaft and constantly meshing with the arm rack, a gear upon the shaft and constantly meshing with the boom rack, and means upon the carriage 75 for actuating the shaft, said dipper arm being adapted to swing about the shaft as an axis.

In testimony that I claim the foregoing as my own, I have hereto affixed my signature in the presence of two witnesses.

JESSE L. FAIRBANKS.
